G. EGLOFF

PROCESS FOR BLENDING AND PURIFYING LIGHT HYDROCARBONS

Filed Dec. 31, 1920

Witness,
S. S. Mann

Inventor,
Gustav Egloff.

By Frank L. Belknap, Atty.

UNITED STATES PATENT OFFICE.

GUSTAV EGLOFF, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA.

PROCESS FOR BLENDING AND PURIFYING LIGHT HYDROCARBONS.

Application filed December 31, 1920. Serial No. 434,184.

To all whom it may concern:

Be it known that I, GUSTAV EGLOFF, a citizen of the United States, residing in the town of Independence, county of Montgomery, and State of Kansas, have invented certain new and useful Improvements in Processes for Blending and Purifying Light Hydrocarbons, of which the following is a specification.

10 This invention relates to improvements in processes of blending and purifying light hydrocarbon oils and has as its salient object to simultaneously absorb very light hydrocarbons, as for example, casinghead gaso-
line, from the uncondensable gas by means of an absorbing fluid, as for example, naphtha and purifying the blending material as part of the same operation and preferably in the same receptacle.

20 In the drawing, the single figure is a view, partly in side elevation and partly in vertical section, of the apparatus suitable for carrying out the process.

Referring in detail to the drawing, 1 des-
25 ignates the container which may take the form of a vertically extending cylinder pro-
vided at its upper end with manhole plate 2 and at its lower end with residue drawoff 3, having throttle valve 4. The retort also has

30 a pressure gauge 5. The blended material is drawn off through the discharge line 6 having throttle valve 7 and leading to the upper end of a suitable receiver 8. This receiver 8 has liquid drawoff pipe 9 having

35 throttle valve 10 and is also provided with uncondensable gas outlet pipe 11, having throttle valve 12. The container 1 is adapt-
ed to be substantially filled with a solution of a base and oxide of a metal carried in a

40 vehicle of a solvent fluid. For example, this purifying material may consist of a liquid solution of caustic soda forming a base and litharge forming the oxide of metal. Light hydrocarbon, as for example, naphtha of 48

45 degrees Baumé gravity, may be introduced by means of a pressure pump through line 13 having throttle valve 14. This line 13 preferably terminates in the perforated ex-
tension 15 in the lower end of the container

50 1. The uncondensable gas, as for example, casinghead gas, gases from by-product coke plants, shale oils or other uncondensable gases containing light hydrocarbons may be

introduced by a pressure pump through the pipe 16 having throttle valve 17, the pipe 16 55 terminating in a perforated extension 18 in the lower part of the member 1. Either the uncondensable gas or absorbing liquid or both of them may be introduced at atmos-
pheric temperature or preheated. If an oil 60 of 58 degrees Baumé gravity is desired and 48 degrees Baumé gravity naphtha is used as the absorbing medium, then sufficient un-
condensable gas should be introduced to give the blend the desired gravity. 65

The receptacle 1 and purifying solution may, if desired, be heated by means of the closed coil 19 having valve 20, controlling its inlet and valve 21 controlling its discharge. Hot water or saturated or superheated steam 70 may be passed through the coil or if it is de-
sired to reduce the temperature, then cool-
ing brine may be forced through the coil so as to maintain the temperature of the mix-
ing chamber 1, say at zero or below zero. 75 The uncondensable gas is drawn off through the pipe 11 while the purified blend will be drawn off through the pipe 9.

I claim as my invention:

1. A process of blending light gasoline-
like hydrocarbons contained in uncondensa-
ble gas with a somewhat heavier absorbing
oil consisting in mixing the two and sim-
ultaneously purifying them by passing them
through a solution of a base, of caustic soda, 85
and an oxide of a metal, and in regulating
the temperature of the solution.

2. A process of blending light gasoline-
like hydrocarbons contained in uncondensa-
ble gas with a somewhat heavier absorbing
oil consisting in mixing the two and sim-
ultaneously purifying them by passing them
through a solution of a base and an oxide
of a metal and regulating the temperature
of the solution. 95

3. A process of blending light gasoline-
like hydrocarbons contained in uncondensa-
ble gas with a heavier absorbing oil con-
sisting in mixing the two and simultaneously
purifying them by passing them through a 100
solution of a base of caustic soda and lith-
arge.

4. A process of blending light gasoline-
like hydrocarbons contained in uncondensa-
ble gas with a somewhat heavier absorbing
oil consisting in mixing the two and simul- 105

aneously purifying them by passing them through a solution of a base and an oxide of a metal.

5. A process of blending light gasoline-like hydrocarbons contained in uncondensable gas with a heavy absorbing oil, consisting in mixing the two and simultaneously purifying them while passing them through a solution of a base and an oxide of metal, 10 and in heating the solution through which the gases pass.

6. A process of blending light gasoline hydrocarbons contained in incondensable gas with a liquid hydrocarbon oil, consisting 15 in bringing said substances into physical contact in a treating chamber where a

complete mixing thereof occurs, and in simultaneously passing the mixed substances through a purifying bath.

7. A process of blending light gasoline hydrocarbons contained in incondensable gas with a liquid hydrocarbon oil, consisting in bringing said substances into physical contact in a treating chamber where a complete mixing thereof occurs, in simultaneously passing the mixed substances through a purifying bath consisting of a solution of a base of caustic soda and an oxide of metal, and in heating such solution during the passage of said substances there- 25 through.

GUSTAV EGLOFF.
